UNITED STATES PATENT OFFICE.

ROBERT B. MCKEE, OF DES MOINES, IOWA.

SANITARY COLLAPSIBLE FRUIT-BOX.

1,251,796.

Specification of Letters Patent.

Patented Jan. 1, 1918.

Application filed October 20, 1915. Serial No. 57,007.

To all whom it may concern:

Be it known that I, ROBERT B. MCKEE, a citizen of the United States, residing at Des Moines, in the county of Polk and State of Iowa, have invented a certain new and useful Sanitary Collapsible Fruit-Box, of which the following is a specification.

The object of my invention is to provide a fruit box of simple, durable and inexpensive construction.

A further object is to provide a fruit box adapted to be made from paper, pressboard, cardboard, or any other suitable material, and to be formed from a single blank properly cut and creased for folding.

Still a further object is to provide such a fruit box so constructed and arranged as to be adapted to be shipped in the flat or to be folded and formed into a completed box without the use of tools, and without the use of any special parts, nails, clips or the like.

Still a further object is to provide such a box having a single bottom member with extensions so arranged as to coact with portions of the side members of the box for forming a solid box, the side of which cannot be collapsed or extended away from the bottom when the box is in use.

My invention consists in the construction, arrangement and combination of the various parts of the device whereby the objects contemplated are attained as hereinafter more fully set forth, pointed out in my claim and illustrated in the accompanying drawings, in which:

Figure 1 shows a top or plan view of a blank from which my improved box is made up.

Fig. 2 shows a similar view of the blank after one fold of the parts has been made. The box blank in Fig. 2 being a slightly modified form in that it does not have the perforations in the bottom which are shown in Fig. 1.

Fig. 3 shows a perspective view of a completed box, and

Fig. 4 shows a vertical sectional view taken on the line 4-4 of Fig. 1.

In the form of my invention illustrated in the accompanying drawings, I have shown a blank which may be stamped or cut from a sheet of oil paper or the like in the form shown in Fig. 1.

My improved boxes are preferably made of water proof paper of sufficient thickness

and rigidity to serve the purpose, but may be made of any suitable material.

The blank comprises an elongated rectangular member having the vertical creases indicated in the accompanying drawings by 60 the reference character 10, by which the rectangular blank is divided into four side members 11, and overlapping and interlocking side members 12. The member 12 is provided at its upper edge with a slot or 65 notch 13, whereby there is formed at the upper outer corner of the member 12 a tongue 14 adapted to be received in a horizontal slot 15 formed in the side member 11 at the opposite end of the blank.

The blank is provided with a horizontal crease 16 near its lower edge. Below the crease 16 is a portion 17 adapted to be folded upwardly and inwardly, as shown in Fig. 2, when the box is assembled.

Formed on the portion 17, opposite one of the side members 11, is a bottom member 18 having on its three free sides or edges, the extensions 19 adapted to be folded downwardly when the box is assembled.

The corners of the members 19 are cut away at 20 and 21 as shown in Fig. 1 to permit the members 19 to be folded upwardly to vertical position without overlapping at the ends. The bottom 18 may be 85 made solid as shown in Fig. 2, or may be provided with perforations 22, as shown in Fig. 1, for furnishing air to the contents of the box.

In the folding and assembling the boxes 90 for use, the blank is laid flat on a table or the like in the position shown in Fig. 1. The bottom 18 and the strip 17 at the lower end of each side member 11 and the lower end of the member 12 are folded upwardly 95 adjacent to the members 11 and 12, as shown in Fig. 2. The blank is then raised to vertical position and the bottom member 18 is lowered to horizontal position, and the members 19 are bent downwardly. The members 11 are then folded along the crease 10 at the corners of the box to the position shown in Fig. 3 with the members 19 extended downwardly between the members 17 and 11, as clearly shown in Fig. 2. The 105 member 14 is inserted through the slot 15, as shown in Figs. 3 and 4. The box is thus completed.

The advantage of a box of this kind from an ordinary wooden box is obvious. In the 110

first place my boxes may be made from moisture proof paper or the like. The ordinary wooden box takes up the juice from the berries, becomes unsanitary, and then attracts gnats and flies, and is impossible to clean. 5 My boxes, when made of paper or the like, will not take up the berry or fruit juice and can be readily and easily washed. The ordinary wooden boxes are fastened together 10 by means of tacks or clips and cannot be collapsed for shipping or storage in the flat.

One type of wooden box, which is collapsible in form, has a bottom made up of a plurality of parts so arranged that they 15 will permit the sides of the box to buckle or bend inwardly. The construction of my improved fruit box is such that the bottom member 18 is of the same size as the interior of the box, so that it engages all four sides 20 of the box and prevents their being bent inwardly.

The members 19 extending downwardly into the space between the members 17 and 11 tend to grip the box sides and hold them 25 together against spreading. Even after the box has been completed it may be readily taken apart and laid out in the flat if desired.

My improved box, on account of its peculiar construction, will retain its shape under almost any condition, as I have found by filling it with sand both wet and dry.

It will be understood that some changes

may be made in the construction and arrangement of the parts of my device without departing from its essential features and purposes and it is my intention to cover by this application any such changes which may be included within the scope of my claim. My box may be used with or without a lid. 40

I claim as my invention:

A collapsible fruit box comprising a single blank folded to form the four walls of the box, one wall having at one end an extension overlapping another wall, said extension being provided at its upper edge near its free end with a vertical slit, the overlapped wall being provided with a horizontal slit to receive the tongue formed adjacent to said first slit, whereby the upper end of the first slit will be inside of and adjacent to the top of the completed box in the assembled device, one of the walls of said box having a portion folded upwardly on the inside, and a bottom secured to the upper edge of said last named portion, the bottom and the other side walls being provided with coacting members for limiting the downward movement of the bottom. 50

Des Moines, Iowa, May 26, 1915.

ROBERT B. MCKEE.
